UNITED STATES PATENT OFFICE.

PAUL C. RAWLS, OF KANSAS CITY, MISSOURI, ASSIGNOR TO ERNEST HAUSBERG, OF CHARLES CITY, IOWA.

ELECTRICALLY-OPERATED TYPE-WRITER.

1,268,491.

Specification of Letters Patent.

Patented June 4, 1918.

Application filed January 8, 1914. Serial No. 811,103.

To all whom it may concern:

Be it known that I, PAUL C. RAWLS, a citizen of the United States, residing at Kansas City, in the county of Jackson and 5 State of Missouri, have invented a certain new and useful Electrically-Operated Type-Writer, of which the following is a specification.

My invention relates to and consists in 10 certain new and useful improvements in electrically operated typewriters of the class illustrated and described in my United States Letters Patent 1,186,941, dated June 13th, 1916. In the application therefor there 15 was a series of selective magnets, one of which was actuated upon the depression of a key so that a certain corresponding type bar would be selected for the next operation; there was also, in circuit with each of the selec- 20 tive magnets, a universal magnet and an armature therefor, which would be energized at the same time as a selective magnet and would close a separate electrical circuit through a power magnet, the latter having 25 an armature and universal power bar connected therewith for completing the operative movement of the selected type bar. In said former application there were means provided for insuring a complete stroke of 30 the type bar even though the contact at the key should not continue during the whole time required for the stroke; and also for effecting a return of the type bar to normal position even though the contact at the key 35 should not be released. The means for accom- plishing both of these results were, how- ever, mechanical rather than electrical; the contact for the power magnet being insured for a full stroke of the type bar by a mechani- 40 cal latching device which held the contact closed until the forward movement of the power armature released it; and the return of the type bar, irrespective of the release of the key, being effected by a mechanical 45 latching device by which the connection between the power bar and the power armature was released through the movement of the latter toward its magnet.

In United States Letters Patent, Number 50 1,209,961, issued December 26, 1916 to Ernest Hausberg, which is for an electrically op- erated typewriter of the same class, the ar- mature of the universal circuit closing mag-

net is connected with a switching device which is thrown over by the circuit closing 55 magnet so as to close the circuit for the power magnet and is held in that position by a spring until the movement of the power armature throws it back again and thereby opens the circuit for the power mag- net. By that device the type bar is re- turned to normal position through the break- 60 ing of the power circuit and my own me- chanical device for that purpose is elimi- nated; but the switching device is made up 65 of mechanical elements which necessarily in- volve some lost motion, are liable in time to become worn and get out of order, and are not as positive and smooth in their action as 70 might perhaps be desired.

In my present invention, I have eliminated 75 all springs, latches or other mechanical means for keeping the power circuit closed during a full stroke of the type bar, and have employed means entirely electrical for 80 accomplishing the purpose; and I have also eliminated all mechanical means for break- 85 ing the power circuit, and have substituted electrical means therefor, the movement of the power armature toward its magnet 90 merely making an electrical contact (or contacts), instead of moving any mechani- cal devices. Such electrical contact accom- plishes the purpose intended by affecting the 95 current in the circuit making and breaking magnet (or magnets) and thus moving the armature of said magnet. In the Hausberg patent just mentioned, it will be observed that the armature of that magnet is not af- fected by the movement of the power arma- 100 ture, but that only related mechanical ele- ments are moved.

The object of my present invention is to 105 provide an electrically operated typewriter of simple, durable, and inexpensive con- struction which shall be capable of working rapidly, smoothly, and with little effort on the part of the operator.

A further object is to provide in a type- 110 writer of this class simple and durable de- vices whereby, when any key is depressed for either a short or a long period of time, the various operations necessary to complete the printing of a character and to return the type bar to position will be progressively 115 carried out.

- 5 A further object is to provide means in a machine of the class described for breaking the circuit of the power magnet upon the completion of the type bar stroke irrespective of any release or movement of the key.
- 10 6 A further object is to provide means for instilling a full and complete stroke of any type bar upon the depression of its key, whether said depression continues during the full stroke or not.
- 15 7 A further object is to accomplish the ends contemplated by means of mechanism which is electrical, as distinguished from mechanical, in its operation, so that the movements 70 of the parts shall be rapid and positive, and so that noise, wear, lost motion, and the liability of the parts to get out of order, shall be reduced to a minimum.
- 20 8 My invention consists in the construction, arrangement and combination of the devices, whereby the objects contemplated are attained, as hereinafter more fully set forth, pointed out in my claims and illustrated in the accompanying drawings, in which:
- 25 9 Figure 1 shows a vertical, longitudinal, sectional view through a typewriter embodying my invention, some of the electrical devices being illustrated diagrammatically, and
- 30 10 Fig. 2 illustrates diagrammatically the construction and arrangement of the electrical elements of my improved typewriter, parts of said diagram being illustrated by mechanical structures for the purpose of 95 35 making the illustration more readily understandable.
- 15 11 In the application of Ernest Hausberg above referred to, there are set forth at considerable length the construction and 100 40 operation of the complete typewriting machine. The present application covers only certain limited parts of the invention of the complete typewriting machine and therefore reference is had to said former application for a full and complete description 105 45 of such of the parts as are not herein fully described.
- 15 12 The reference numeral 19 indicates generally the frame of the machine and 11 the 110 50 keys. When any key is depressed its spring 12 forms a contact with the conductor bar 13 and closes a circuit through the corresponding selective magnet 14, as more fully set forth in the said application of Ernest 115 55 Hausberg. For each selective magnet there is an armature 15, connected by a link 16 with a hook lever 17. This hook lever 17 is pivoted to a lever 18, which in turn is operatively connected to a type bar 19 so that 120 60 when the lever 18 is moved rearwardly the type bar will be operated. Adjacent to the lever 18 is a power bar 20 connected by a link 21 to a universal power armature 22. This power bar 20 is positioned so that it 125 65 will be engaged by the hook lever 17 when

the latter, upon the depression of a key, is drawn downward by the armature of the corresponding selective magnet, and when the power armature is moved rearwardly the power bar 20 and the upper end of the lever 18 will also be moved rearwardly, thus causing the type bar to be operated. The movable carriage of the typewriter is indicated generally by the reference numeral 23. The upper parts of the brackets 22^a serve as 75 a stop to limit the forward movement of the arms carrying the power armature.

The electrically operated parts of my invention, which are illustrated particularly in Fig. 2, are as follows: The reference numeral 24 indicates a battery or other source 80 of electrical energy connected by a conductor wire 25 to the conductor rods 26 under the keys 11. Each key rests upon a conductor spring 27 and when the spring is depressed 85 by the key contact is made with the adjacent conductor bar 26. A condenser 28 is preferably provided between the conductor 25 and the conductors leading from the springs 27 for the purpose primarily of preventing 90 sparking. In the diagram illustrated in Fig. 2, the selective magnets 14 are illustrated by coils, which are connected by conductors 29 with the springs 27.

During the operation of writing on a machine of this kind, it sometimes happens that a key is depressed only for a very short space of time and it sometimes happens that an operator permits his finger to rest upon a key for a comparatively long time.

100 It is desirable in a machine of this class to have the type bar complete its printing stroke even though the depression of the key does not continue during the stroke, and to have the type bar return automatically to its normal position even though the depression of the key continues beyond the time required for the printing stroke. In order to accomplish these objects most effectively, it is necessary: first, that a selective magnet be 105 energized and that the hook 17 be moved into engagement with the universal bar 20 (for which only a momentary depression of the key is necessary); second, that the universal power magnet, which is indicated generally by the reference numeral 30, be energized and a circuit maintained therein for a sufficient length of time to complete the printing stroke of the type bar regardless of whether or not the contact is maintained at the key; and third, that the circuit through the power magnet be broken at the completion of the printing stroke to permit the return of the type bar.

110 115 120 These three general operations just referred to are carried out in my improved machine as follows:

125 The first operation, that of energizing the selective magnet and thereby lowering the hook lever 17, has already been described.

For performing the second operation, the specific mechanism herein shown and described is as follows:

The numeral 31 indicates a movable switch 6 normally held in a neutral position by a spring 32 capable of moving either rearwardly or forwardly against the spring pressure. Arranged in front of the switch 31 is an electromagnet 32^a and arranged in 10 the rear of the switch 31 is another electromagnet 33. An armature 31^a is fixed to switch 31 and is adapted to be actuated by both magnets 32^a and 33. When a contact is made at a key 11, a current will flow from 15 one side of the battery 24 through the conductor 25 to the contact 26, thence through the conductor 29, selective coil 14 and conductor 34 and this current will be divided and part of it flow through the conductor 35 20 and part through the conductor 36. Connected with the conductor 35 is a coil 37 on the magnet 32^a which is connected by the return wire 38 and the return wire 39 to the battery 24. The part of the current that goes 25 through the conductor 36 also goes through a coil 40 on the electromagnet 33 and returns through the conductor 41 to the conductor 39 and back to the battery. The said coil 37 is arranged so that it has approximately 30 twice the amount of resistance as the coil 40 so that when both coils are energized the magnet 33 will overcome the pull 35 of the magnet 32^a and cause the switch 31 to move rearwardly. When the switch 31 is moved rearwardly a circuit is established from the battery to the power magnet 30 as follows:

A conductor 42 connects the battery with the switch 31 and when the switch 31 40 is moved toward the rear a circuit is completed at 63 through the switch 31 to the conductor 43, which conductor connects to the coil 44 on the power magnet 30, and from the coil 44 the return wire 45 leads 45 to the battery.

It is possible of course that after the key 50 has been depressed and the current passed momentarily through the power magnet, as before described, the key will be released and the circuit broken. In order to insure the completion of the type bar movement, even though the key is released, I have provided a second coil 46 on the magnet 33, preferably of high resistance, connected to a conductor 55 47 at one end and to the return wires 48 and 39 at the other end, so that instantly upon the movement of the switch 31 to the rear, a circuit is established from the battery through the switch 31 and through this 60 coil 46 to further energize the said magnet 33 and thereby hold the switch 31 rearwardly even though the current through the first coil 40 on the magnet 33 is discontinued. After the establishing of this new circuit 65 through the magnet 33, the circuit through

the power magnet is then maintained regardless of the position of the key and the armature 22 is drawn toward the power magnet.

The universal magnets 32^a and 33 and the 70 switch 31 may of course be made as small, and the spring as delicate, as desired so that the action of the switch in making the power circuit and the action of the selective magnet in lowering the hook will be practically 75 simultaneous.

In order to perform the third operation, to wit: the break in the circuit through the power magnet to permit the return of the type bar, I have provided on the power 80 magnet the contact arm 53 and on the power armature a contact arm 54. The contact arm 53 is connected to a conductor 55, which is in turn connected with the conductors 62 and 34, and the contact arm 54 is connected 85 to a conductor 56 which leads to the coil 57 on the magnet 33, which coil is wound on said magnet in a reverse direction from the coils 40 and 46 so that when a circuit is established through this coil 57, it neutralizes the magnet 33, thus permitting the spring 32 to move the switch 31 toward the front. This movement of course is assisted by the magnet 32^a, which has remained 90 partially energized during this entire operation. However, in order to insure the magnet 32^a being sufficiently energized to move the switch 31 toward the front, a branch conductor 58 is connected to the conductor 56 and this branch conductor is connected to the coil 59 on the magnet 32^a, to thereby increase the magnetic power. The said coil 59 is connected by a return wire 60 with the conductor 39, which returns to the battery. Obviously when the switch 31 is thus moved toward the front, the circuit for the power magnet will be broken and the power armature may again move forwardly and the type bar will be returned to 100 normal position.

In order however that these operations may be performed as described, it is of course necessary that when the contact arms 53 and 54 come together, there be an electrical current to be established through 115 them. Whatever current there is must flow through the contact formed at the key. But if the contact at the key has been broken before the contact at 53 and 54 is made, it is obvious that the latter contact will have no effect whatever; the switch 31 will then continue to be held in its rearward position and the power magnet will continue to be energized, with the result that the type bar will be held rigidly against 125 the platen until a key is again depressed. To overcome this difficulty, I have provided that the rearward movement of the power armature shall not only make the contact between the arms 53 and 54, but shall at 130

the same time (or at any time after the power armature starts its rearward movement) make a second contact to supplement, or take the place of, that at the key. The 5 means described comprises two yielding contact arms 49 and 50, connected respectively with the magnet 30 and the armature 22. The arm 49 is connected by conductors 51, 42^a and 42 with one side of the battery 10 24, and the arm 50 is connected by the conductor 52 with the conductors 35 and 36, so that, as soon as the armature 22 makes a slight movement toward the power magnet, an independent circuit from the battery 24 15 is set up through the conductors 42, 42^a, 51, arms 49 and 50, and conductor 52 to take the place of the circuit originally established through the conductor 34 by the depression of a key.

20 Assuming that even after the movement of the type bar has been completed, the operator still maintains pressure upon the key, obviously it is not desirable that this key contact should result in repeated movements of the same type bar, and in order to prevent this I have provided the following devices:

25 On the switch 31 is a contact plate 67 so arranged that when the switch 31 is at its forward limit a circuit will be established between the conductors 62 and 39, which will result in preventing the circuit established by the depression of the key from moving the switch 31 rearwardly because a 30 circuit will be established through the key and the conductors 27, 29 and 62, through the coil 59 which, in connection with the circuit already established by the depression of the key through the coil 37, will be 35 sufficiently energize the magnet 32^a to hold the switch 31 forwardly. As soon as the circuit is established through the coil 59, as before described, a circuit will also be established through the branch conductor 58 40 and through the reverse coil 57 on the magnet 33, thus neutralizing the effect of the other coils on the magnet 33. It will be seen that the contact plate 67 simply takes the place of the contact arms 53 and 54. Hence, as long as the key remains depressed, the switch 31 will be at its forward limit and no further operation of the type bar may be made until said key is released, and upon a release of the key all of the 45 circuits are broken and the switch 31 may then return by means of its spring to a neutral position, as shown in Fig. 2. I preferably provide a condenser 64 between the conductors 43 and 51 to prevent sparking at 50 the contact 63.

55 In the practical operation of my improvement, the first effect of a depression of a key is to establish a circuit through a selective magnet and at the same time through 60 the coils 37 and 40. The coil 37 has more

resistance than the coil 40 and hence the electromagnet 33 will be energized sufficiently to move the switch 31 rearwardly. When this switch is moved rearwardly, an independent circuit from the battery is established through the switch 31 and through the coil 44 on the power magnet, and at the same time a circuit is established through the coil 46 on the magnet 33, thus energizing this magnet to positively hold the 70 switch 31 regardless of whether or not the original circuit is broken. Hence a complete power armature stroke is insured. As soon as the power armature moves toward the power magnet, another circuit is established 75 through the contacts 53 and 54 and the establishing of this independent circuit causes the magnet 33 to be neutralized because the coil 57 thereon is arranged in a reverse direction from the other coils. At the same 80 time a circuit is established through the coil 59, which is wound in the same direction as the other coil 37, of the magnet 32^a, and hence serves to reinforce it and aid in moving the switch 31 forwardly or toward the 85 magnet 32^a so as to break the circuit for the power magnet. In this circuit the current flows from one side of the battery through the conductor 25, contact 26, conductor 29, selective coil 14, conductors 34, 62 and 55, 90 contacts 53 and 54, conductors 56 and 58, the coil 59, and thence through the conductors 60 and 39 to the other side of the battery.

95 It is necessary to provide means for preventing repeated operation of the type bar 100 in case the depression of the key continues. For this purpose the contact device 67 on the switch 31 closes a circuit through the coil 59 on the magnet 32^a, thus augmenting its power, and also through the coil 57 on the 105 magnet 33, thus neutralizing the latter, so that the switch device 31 is positively held toward the magnet 32^a until the key is released. As soon however as the circuit is 110 broken through the key, then the other independent circuits are all broken and the switch 31 may return by its spring to the neutral position, shown in Fig. 2.

115 It will be seen from the foregoing, that, if any key is depressed for a sufficient time to establish a circuit through a selective magnet and the switch operating device, the power magnet will be energized so as to produce a complete stroke of the type bar, whether the key remains depressed during 120 the stroke or not; and that, through the automatic breaking of the circuit of the power magnet the type bar will be returned to normal position whether the key is released or not.

125 It will also be seen that all of the means for progressively controlling the movement of the switch and of the power armature are electrical, as distinguished from mechanical and are not so subject to wear or lost mo- 130

tion, and are not so liable to produce noise as devices of this class that perform these functions through purely mechanical contrivances. Applicant has obtained satisfactory results by leaving the coil 37 open; that is, by disconnecting it from the conductor 35 or the return wire 38, the effect being the same as if the coil 37 were omitted entirely. That is, instead of having two windings such that one takes twice as much current as the other and thus has a stronger pull than the other, the winding giving the weaker pull may be left off altogether. Of course the winding 39 is retained. Applicant therefore does not wish to be understood as limiting himself to the use of a double winding for moving the switch 31 rearwardly.

I claim as my invention:

1. In an electrically operated typewriter, the combination of keys, type bars, selective magnets, means for establishing an electric circuit through a selective magnet upon the depression of a corresponding key, a type bar operating device for each type bar, means actuated by a selective magnet, upon the completion of a circuit through it, for moving a corresponding type bar operating device to operative position, a power magnet, an armature therefor, means operated by said armature for actuating a type bar operating device when the latter has been moved to operative position, a universal magnet energized upon and by the completion of a circuit through any selective magnet, an armature therefor, means operated by said armature for closing a circuit through the power magnet, and means operated upon and by the moving of the power armature 40 toward its magnet for establishing a circuit to cause the armature of the said universal magnet to break the circuit for the power magnet.

2. In an electrically operated typewriter, the combination of keys, selective magnets, means for energizing a selective magnet upon the depression of a key, a power magnet, a power armature, type bars adapted to be operatively connected with the power armature, means actuated by the selective magnets for operatively connecting a selected type bar with the power armature, an electric switch device, means for energizing and thereby moving the electric switch device in one direction upon the completion of a circuit through a selective magnet, means actuated by said switch device for energizing the power magnet, and means actuated upon the movement of the power armature 55 toward its magnet for establishing an independent circuit to cause a return movement of the switch device and thereby a breaking of the circuit through the power magnet.

3. In an electrically operated typewriter, the combination of keys, selective magnets,

means for energizing a selective magnet upon the depression of a key, a power magnet, a power armature, type bars adapted to be operatively connected with the power armature, means actuated by the selective magnet 70 for operatively connecting a selected type bar with the power armature, an electric switch device, means for energizing and thereby moving the electric switch device in one direction upon the completion of a circuit through a selective magnet, means actuated by said switch movement for energizing the power magnet, and means for establishing an independent circuit through the said switch device for maintaining it in 80 its said position independently of the said circuit established through the selective magnet, and means for permitting a return movement of the switch device.

4. In an electrically operated typewriter, the combination of keys, selective magnets, means for energizing a selective magnet upon the depression of a key, a power magnet, a power armature, type bars adapted to be operatively connected with the power 90 armature, means actuated by the selective magnets for operatively connecting a selected type bar with the power armature, an electric switch device, means for energizing and thereby moving the electric switch device in one direction upon the completion of a circuit through a selective magnet, means actuated by said switch movement for energizing the power magnet, and means actuated by a movement of the power armature 95 toward the power magnet for establishing a circuit through the switch device for returning it.

5. In an electrically operated typewriter, the combination of keys, selective magnets, means for energizing a selective magnet upon the depression of a key, a power magnet, a power armature, type bars adapted to be operatively connected with the power armature, means actuated by the selective 105 magnets for operatively connecting a selected type bar with the power armature, an electric switch device, means for energizing and thereby moving the electric switch device in one direction upon the completion of a circuit through a selective magnet, means actuated by said switch movement for energizing the power magnet, and means actuated by a movement of the power 110 armature toward the power magnet for establishing a circuit through the switch device for returning it, and means actuated by a return movement of the switch device and upon the continuance of a circuit through a selective magnet, for establishing a circuit 115 through the switch device tending to hold same against further movement.

6. In an electrically operated typewriter, the combination of keys, selective magnets, means for energizing a selective magnet 120

- upon the depression of a key, a power magnet, a power armature, type bars adapted to be operatively connected with the power armature, means actuated by the selective magnets for operatively connecting a selected type bar with the power armature, an electric switch device, means for energizing and thereby moving the electric switch device in one direction upon the completion of 5
- 10 a circuit through a selective magnet, means actuated by said switch movement for energizing the power magnet, means actuated by a movement of the power armature toward the power magnet for establishing a circuit
- 15 through the switch device for returning it, means actuated by a return movement of the switch device and upon the continuance of a circuit through a selective magnet, for establishing a circuit through the switch device
- 20 tending to hold same against further movement, and a spring for normally returning the switch device to and holding it in a neutral position.
7. In an electrically operated typewriter, 25 the combination of keys, selective magnets, means for energizing a selective magnet upon the depression of a key, a power magnet, a power armature, type bars adapted to be operatively connected with the power armature, means actuated by the selective magnets for operatively connecting a selected type bar with the power armature, a movable switch, two electromagnets, each capable of moving the switch in a different direction, 30 means actuated by a circuit through a selective magnet for moving said switch toward one of said electromagnets, means actuated upon said switch movement for establishing an independent circuit through the power magnet, means actuated upon a movement of the power armature for establishing circuits through said electromagnets tending to move the switch toward the other one of said magnets and means actuated by said latter 35 movement of the switch for establishing a circuit through one of said electromagnets tending to hold it in said position until the original circuit established through the selective magnet has been broken.
- 40 8. In an electrically operated typewriter, the combination of keys, selective magnets means for energizing a selective magnet upon the depression of a key, a power magnet, a power armature, type bars adapted to be operatively connected with the power armature, means actuated by the selective magnets for operatively connecting a selected type bar with the power armature, and a switch device comprising a movable switch member, means for yieldingly holding it in a neutral position, two electromagnets for said movable switch member, one for holding the switch member in its operative position and the other for returning it to an in- 45
- 50 operative position, means actuated upon the completion of a circuit through a selective magnet for energizing both of said switch magnets, the means for energizing the said operative switch magnet being greater than the other means, means actuated upon a movement of the movable switch member toward the operative magnet for establishing an independent circuit through the power magnet, a second means operated upon said movement of the switch member for establishing an independent circuit through the operative switch magnet to thereby hold the switch magnet in position in case the circuit through the selective magnet is broken, and means actuated upon a movement of the power armature for establishing an independent circuit through the said operative magnet in a direction tending to neutralize the other circuits through this magnet and at the same time to establish an independent circuit through the switch returning magnet tending to move the movable switch member toward the switch returning magnet.
- 55 9. In an electrically operated typewriter, the combination of keys, selective magnets, means for energizing a selective magnet upon the depression of a key, a power magnet, a power armature, type bars adapted to be operatively connected with the power armature, means actuated by the selective magnets for operatively connecting a selected type bar with the power armature, and a switch device comprising a movable switch member, means for yieldingly holding it in a neutral position, two electromagnets for said movable switch member, one for holding the switch member in its operative position and the other for returning it to an inoperative position, means actuated upon the completion of a circuit through a selective magnet for energizing both of said switch magnets, the means for energizing the said operative switch magnet being greater than the other means, means actuated upon a movement of the movable switch member toward the operative magnet for establishing an independent circuit through the power magnet, a second means operated upon said movement of the switch member for establishing an independent circuit through the operative switch magnet to thereby hold the switch magnet in position in case the circuit through the selective magnet is broken, means actuated upon a movement of the power armature for establishing an independent circuit through the said operative magnet in a direction tending to neutralize the other circuits through this magnet and at the same time to establish an independent circuit through the switch returning magnet tending to move the movable switch member toward the switch returning magnet.
- 60 10. In an electrically operated typewriter, the combination of keys, selective magnets means for energizing a selective magnet upon the depression of a key, a power magnet, a power armature, type bars adapted to be operatively connected with the power armature, means actuated by the selective magnets for operatively connecting a selected type bar with the power armature, and a switch device comprising a movable switch member, means for yieldingly holding it in a neutral position, two electromagnets for said movable switch member, one for holding the switch member in its operative position and the other for returning it to an in- 65

for completing a second circuit through the switch returning magnet, said circuit being energized by the circuit through a selective magnet for holding the said switch member

5 in an inoperative position as long as a circuit is established through a selective magnet, for the purposes stated.

10. In an electrically operated typewriter, the combination of keys, type bars, selective magnets, means for establishing an electric circuit through a selective magnet upon the making of an electrical contact at a corresponding key, a type bar operating device for each type bar, means actuated by 15 a selective magnet, upon the completion of a circuit through it, for moving a corresponding type bar operating device to operative position, a power magnet, an armature therefor, means operated by said armature 20 for actuating a type bar operating device when the latter has been moved to operative position, a universal magnet energized upon and by the completion of a circuit through any selective magnet, an armature therefor, 25 means for moving the said armature to close a circuit through the power magnet, and means automatically operated upon the movement of the power armature toward its magnet and irrespective of the breaking of 30 the circuit through the selective magnet for effecting a movement of the armature of the said universal magnet to break the circuit of the power magnet.

11. In an electrically operated typewriter, the combination of keys, type bars, selective magnets, means for establishing an electric circuit through a selective magnet upon the depression of a corresponding key, a type bar operating device for each type bar, 35 means actuated by a selective magnet, upon the completion of a circuit through it, for moving a corresponding type bar operating device to operative position, a power magnet, an armature therefor, means operated 40 by said armature for actuating a type bar operating device when the latter has been moved to operative position, means operated upon the making of an electrical contact at a key for energizing the power magnet, and means operated upon the making of an electrical contact by the power magnet for breaking the circuit of said magnet.

12. In an electrically operated typewriter, having means operatively connected with the keys for moving type bar devices to position to be operated and having a power magnet for moving a selected type bar device to printing position, the combination of a 45 circuit closing and opening device also operatively connected with the keys, said device being provided with a circuit and having means for closing the circuit of the power magnet, and means operatively con-

nected with the armature of the power 65 magnet for closing said circuit through the circuit closing and opening device to break the circuit of the power magnet.

13. In an electrically operated typewriter having selective magnets for moving type 70 bar devices to position to be operated and a power magnet for moving the selected type bar device to printing position, the combination of a circuit closing and opening device provided with a circuit and having 75 means for closing the circuit of the power magnet, and means operatively connected with the armature of the power magnet for establishing a circuit through the circuit closing and opening device to break the circuit of the power magnet.

14. In an electrically operated typewriter, the combination of keys, selective magnets, means for energizing a selective magnet upon the making of an electrical contact at 85 a key, a power magnet, a power armature, type bars adapted to be operatively connected with the power armature, means actuated by the selective magnets for operatively connecting a selected type bar with 90 the power armature, a movable switch, two electromagnets each capable of moving the switch in a different direction, means actuated upon the establishment of a circuit through a selective magnet for moving the switch toward one of the said electromagnets, means actuated upon the said switch movement for establishing an independent circuit through the power magnet, and means operated upon a movement of the 100 power armature for establishing a circuit tending to move the switch toward the other one of the said magnets.

15. In an electrically operated typewriter, the combination of keys, selective magnets, means for energizing a selective magnet upon the making of an electrical contact at a key, a power magnet, a power armature, type bars adapted to be operatively connected with the power armature, means actuated by the selective magnets for operatively connecting a selected type bar with the power armature, a movable switch, two electromagnets each capable of moving the switch in a different direction, means actuated upon the establishment of a circuit through a selective magnet for moving the switch toward one of the said electromagnets, means actuated upon the said switch movement for establishing an independent 110 circuit through the power magnet, means operated upon a movement of the power armature for establishing a circuit tending to move the switch toward the other one of the said magnets, and means actuated by the 115 said latter movement of the switch for establishing a circuit tending to hold it in the said position until the original circuit es-

tablished through the selective magnet has been broken.

16. In an electrically operated typewriter, the combination of keys, selective magnets, means for energizing a selective magnet upon the making of an electrical contact at a key, a power magnet, a power armature, type bars adapted to be operatively connected with the power armature, means actuated by the selective magnets for operatively connecting a selected type bar with the power armature, a movable switch, two electromagnets each capable of moving the switch in a different direction, means actuated upon the establishment of a circuit through a selective magnet for moving the switch toward one of the said electromagnets, means actuated upon the said switch movement for establishing an independent circuit through the power magnet, means operated upon a movement of the power armature for establishing a circuit tending to move the switch toward the other one of the said magnets, means actuated by the said latter movement of the switch for establishing a circuit tending to hold it in the said position until the original circuit established through the selective magnet has been broken, and a spring for normally returning the switch to, and holding it in, a neutral position.
17. In an electrically operated typewriter, the combination of keys, selective magnets, means for energizing a selective magnet upon the depression of a key, a power magnet, a power armature, type bars adapted to be operatively connected with the power armature, means actuated by the selective magnets for operatively connecting a selected type bar with the power armature, a switch device comprising a movable switch member, two electromagnets for said movable switch member, one for holding the switch member in its operative position and the other for returning it to an inoperative position, means actuated upon the completion of a circuit through a selective magnet for causing the switch member to be drawn toward one of said magnets, means actuated upon a movement of the movable switch member toward the operative magnet for establishing an independent circuit through the power magnet, a second means operated upon said movement of the switch member for establishing an independent circuit through the operative magnet in a direction tending to neutralize the other circuits through this magnet and at the same time to establish an independent circuit through the switch returning magnet tending to move the movable switch member toward the switch returning magnet, and a contact device carried by said movable switch member for maintaining the circuit through the switch returning magnet, said circuit being energized by the circuit through a selective magnet for holding the said switch member in an inoperative position as long as a circuit is established through a selective magnet for the purpose stated.
18. In an electrically operated typewriter, the combination of keys, selective magnets, means for energizing a selective magnet upon the depression of a key, a power magnet, a power armature, type bars adapted to be operatively connected with the power armature, means actuated by the selective magnets for operatively connecting a selected type bar with the power armature, a switch device comprising a movable switch member, two electromagnets for said movable switch member, one for holding the switch member in its operative position and the other for returning it to an inoperative position, means actuated upon the completion of a circuit through a selective magnet for causing the switch member to be drawn toward one of said magnets, means actuated upon a movement of the movable switch member toward the operative magnet for establishing an independent circuit through the power magnet, a second means operated upon said movement of the switch member for establishing an independent circuit through the power magnet, a second means operated upon the completion of a circuit through a selective magnet for causing the switch member to be drawn toward one of said magnets, means actuated upon a movement of the movable switch member toward the operative magnet for establishing an independent circuit through the power magnet, a second means operated upon said movement of the switch member for establishing an independent circuit through the operative magnet in a direction tending to neutralize the other circuits through this magnet and at the same time to establish an independent circuit through the switch returning magnet tending to move the movable switch member toward the switch returning magnet, and a contact device carried by said movable switch member for maintaining the circuit through the switch returning magnet, said circuit being energized by the circuit through a selective magnet for holding the said switch member in an inoperative position as long as a circuit is established through a selective magnet for the purpose stated.
19. In an electrically operated typewriter having means operatively connected with the keys for moving type bar devices to position to be operated and also having a power magnet for moving a selected type bar device to printing position, the combination of a circuit closing and opening device also operatively connected with the keys, said device being provided with circuits and having means for closing the circuit of the power magnet, and means operated upon the movement of the armature of the power magnet caused by closing the power magnet circuit for affecting the circuits of the circuit closing and opening device so as to cause it to break the circuit of the power magnet.
20. In an electrically operated typewriter, the combination of keys, a power magnet, an electric circuit therefor, a power armature, type bars adapted to be operatively connected with the power armature,

- means actuated upon the depression of a key for operatively connecting a corresponding type bar with the power armature, a movable switch member, two electromagnets, an armature therefor operatively connected with said switch member, means also actuated upon the depression of a key for causing said armature to be drawn toward one of said magnets to close the circuit of the power magnet, and means actuated upon a movement of the power armature for causing the armature of the two electromagnets to be drawn toward the other of said magnets to break the circuit of the power magnet.
21. In an electrically operated typewriter, the combination of keys, a power magnet, a circuit therefor, an armature for the power magnet, type bars adapted to be operatively connected with the said armature, means actuated upon the depression of a key for operatively connecting a corresponding type bar with the said armature, a movable switch member, means also actuated upon the depression of a key for causing a movement of the said switch member to close the circuit of the power magnet, an electromagnet for retaining the switch member in such closed position, a circuit therefor, and means also operated by the said movement of the switch member for closing the circuit of the said electromagnet.
22. In an electrically operated typewriter, the combination of keys, a power magnet, a circuit therefor, an armature for the power magnet, type bars adapted to be operatively connected with the said armature, means actuated upon the depression of a key for operatively connecting a corresponding type bar with the said armature, a movable switch member, means also actuated upon the depression of a key for causing a movement of the said switch member to close the circuit of the power magnet, an electromagnet for retaining the switch member in such closed position, a circuit therefor, and means also operated by the said movement of the switch member for closing the circuit of the said electromagnet.
23. In an electrically operated typewriter, the combination of keys, a power magnet, a circuit therefor, an armature for the power magnet, type bars adapted to be operatively connected with the said armature, means actuated upon the depression of a key for operatively connecting a corresponding type bar with the said armature, a universal magnet, an armature therefor, means operatively connected with the armature of the universal magnet for closing and breaking the circuit of the power magnet, means also operated upon the depression of a key for effecting a movement of said armature to

close the circuit of the power magnet, and means operated by a movement of the power armature for effecting a movement of the armature of the said universal magnet to break the circuit of the power magnet irrespective of the release of the key.

24. In an electrically operated typewriter, the combination of keys, a power magnet, a circuit therefor, an armature for the power magnet, type bars adapted to be operatively connected with the said armature, means actuated upon the depression of a key for operatively connecting a corresponding type bar with the said armature, a movable switch member, means also actuated upon the depression of a key for causing a movement of the said switch member to close the circuit of the power magnet, an electromagnet for retaining the switch member in such closed position, a circuit therefor, and means also operated by the said movement of the switch member for closing the circuit of the said electromagnet.

Des Moines, Iowa, Dec. 4, 1913.
